UNITED STATES PATENT OFFICE.

CHARLES H. NITSCH, OF PHILADELPHIA, PENNSYLVANIA, ASSIGNOR TO STOKES AND SMITH COMPANY, OF PHILADELPHIA, PENNSYLVANIA, A CORPORATION OF PENNSYLVANIA.

MACHINE FOR PRESSING NECKS IN BOXES.

1,397,597.

Specification of Letters Patent.

Patented Nov. 22, 1921.

Application filed July 29, 1919. Serial No. 313,969.

To all whom it may concern:

Be it known that I, CHARLES H. NITSCH, a citizen of the United States, residing at Philadelphia, in the county of Philadelphia and State of Pennsylvania, have invented 5 new and useful Improvements in Machines for Pressing Necks in Boxes, of which the following is a specification.

My invention relates to machines for making paper boxes, and particularly to a machine for pressing the necks in position in necked box bodies.

My invention comprises a machine of the type commonly known as a "neck presser" 15 in the art, an example of which is disclosed in the patent to Philip S. Smith #748,429. The machines of this kind are used in the production of the type of paper box in which a vertical strip or neck is glued to 20 the inside of the body portion of the box and projects above its upper edge to form a flange over which the cover is placed with its edges butting the edges of the box body, producing a flush side. In introducing 25 necks in box bodies, the glue is applied to the inside of the body and the neck inserted by hand. Originally, the entire process of fixing the neck in position was performed by hand. Subsequently, neck pressers were developed, in the use of which it 30 is only necessary for the operator to loosely locate the neck in the glued box body and to position the body with the neck therein over a form. The press is then applied to 35 the box on the form and the neck pressed firmly into contact with the box body. This method of procedure not only insures continuous, even contact but avoids finger marks and smears incidental to handling, 40 in addition to considerable speeding up the process. By this method, however, the box is both inserted and removed by hand, necessitating considerable manual labor and slowing up the press action because the 45 press must be held in open position while the operator removes a box therefrom and inserts another in its place.

An object of my invention is to produce an improved machine which will be much 50 more rapid in operation, both because of the improved arrangement of the parts, and because of additional features which elimi-

nate part of the handling of the boxes by the operator. One improved feature is the location of the presser table in an approximately vertical position, preferably slightly inclined rearwardly so that the boxes will remain therein through gravity. This enables the operator to place the box body in the press without reaching over the table, 60 making the path of the box from the feed table to the press much shorter and the operator's work correspondingly quicker.

I have also provided means for automatically removing the box from the presser, 65 entirely eliminating any handling thereof by the operator after the box is once inserted in the press. This means includes both a device for ejecting the box from the press, and a convenient conveyer for carrying the box to a delivery point at one side of the press. I have also arranged my press, 70 ejector and conveyer in such a way that the ejected box falls on the conveyer by gravity, this arrangement permitting the use of a 75 very simple ejecting and conveying mechanism.

Furthermore, I provide a single fixed form mounted on the press, upon which the operator locates the box body, with the neck 80 loosely placed therein, while the press is open. After the box is pressed, the ejecting mechanism removes it from the form, leaving the latter ready for the next box body and neck. This method of operation enables the operator to handle the boxes very 85 rapidly, as they are light and readily positioned on a firmly mounted form. I have so constructed my press that a form of any desired size and shape may be quickly and 90 easily substituted for the form in the press and the press members readily adjusted to the new form or replaced by other members suited to coöperate with the new form.

I have also produced an improved press 95 mechanism. I have provided a single driving element for all four presser blocks of each press, simplifying the drive substantially and assuring perfect synchronization. I also reciprocate all of the presser blocks, 100 as it is only necessary, with this construction, to move each block half the distance required in the Smith neck presser in order to provide the same amount of clearance. Fur-

ther, I have made the two presses entirely independent of each other save for a common drive shaft, and have arranged the parts so that they may readily be removed and replaced, the whole table and its mechanism being readily removable. I also have provided an improved resilient mounting for the presser blocks, adapted for adjustment to insure even pressure throughout the block.

10 The vertical arrangement of my press has facilitated the mounting in the rear thereof of a neck gluing machine such as the one referred to, and I have provided a table across one end of the frame along which 15 the glued boxes with the necks loosely inserted are fed by the gluing operator. This is a further advantage of the vertical table and economizes floor space while it facilitates rapid handling of the boxes.

20 While certain features of my invention are improvements on the Smith neck presser, it will be apparent that many of them are distinct departures therefrom, and are applicable broadly to other presses or similar 25 machines of various kinds.

Other objects and advantages of my invention will be apparent from the following description taken in connection with the accompanying drawings, in which:

30 Figure 1 is a front view, parts being broken away,

Fig. 2 is an end view from the right hand side of Fig. 1,

35 Fig. 3 is a plan view of the table with the presser block structure removed from the left hand press, part of the table being broken away to show the drive,

40 Fig. 4 is a top view of the table and the driving mechanism, the right half being shown in plan, the left half in transverse horizontal section through the center of the press and through the center of the drive shaft, and

45 Fig. 5 is a detail plan view of the presser block mounting, the mounting head being shown in central horizontal section.

Similar reference numerals refer to similar parts throughout the drawings.

My neck presser is carried by a frame consisting preferably of end members 10 and 11 upon which is removably mounted by bolts or screws 12 the press table 13, in approximately vertical position, being preferably tilted slightly backward. On the front of 55 the table is mounted presser mechanism which may consist of any preferred number of presses, two being shown in the form illustrated. These presses are exact duplicates and independent of each other. Each comprises a plurality of presser blocks 14, ordinarily wooden blocks properly shaped to fit the contour of the box to be pressed and which may carry on their inner faces pads 15 of any desired material. Each block is 60 held in a clamp 16 having upper and lower

jaws, a set screw 17 being mounted in the upper jaw to adjustably clamp the block in position. As shown in Fig. 5, each clamp carries two studs 18, removably mounted on the rear face of the clamp, as by threading them into sockets therein. Each stud has a head 19 slidably mounted in a chamber 20 in the presser block carrier head 21, the front end of the chamber being apertured to form a loose guideway for the shank of a 70 stud 18. A helical spring 22 is located in each chamber and presses outwardly against the head of each stud, the rear end of the spring bearing against an adjusting screw plug 23 threaded into the outer end of the 80 chamber, the tension of each spring being readily adjusted by means of said plug. Each carrier head 21 is adjustably mounted on a longitudinally slotted slide 24 in any desired way. I preferably use a bolt 25, 85 passing vertically through the carrier head and the slot to clamp the carrier head 21 adjustably on slide 24. Slide 24 rests upon the surface of table 13, or, if desired, upon a slightly raised portion thereof, said table 90 being cut away beneath the slide slot to provide clearance for the head of the carrier bolt. This head is preferably elongated in shape, being normally located transverse to the slot, but as it is narrower than the slot, 95 the carrier may be readily removed by loosening the bolt and rotating it through a quarter revolution to bring the head in line with the slot. Slide 24 reciprocates in ways of any desired construction. I prefer to provide a pair of ways 27 suitably formed to accommodate the edges of the slide, which may be beveled, the ways being removably mounted on table 13, as by screws. It will be apparent that the slide and presser block 100 carrying mechanism may be entirely removed by the removal of ways 27, facilitating the repair and replacement of parts. Obviously, various other methods of mounting the presser blocks may be used without 110 affecting the operation of other parts of my invention, and the specific type of mounting shown is applicable to a variety of machines.

Each of the slides 24 has projecting downwardly from its forward end a hub 28, best 115 shown in Fig. 4, carrying a stud 29, on which is mounted a roller 30, fitting into groove 31 in the face of disk cam 32, lying parallel to and below the surface of the table, said cam being mounted on stub shaft 120 33, which has a reduced end fitting in a socket in the table. Cam 32 is provided with a rearwardly projecting hub 34 on which is mounted worm gear 35 fixed to said hub as by key 36. The rear end of stud 33 125 is reduced, and fits into a socket in casing 37, which is shaped to house the drive mechanism at the rear of the table, and is detachably mounted thereon. It will be noted that stub shaft 33 is shouldered adjacent its 130

sockets in the table and housing, providing for positive location of the shaft in place when the housing is in position and facilitating the ready removal thereof upon removal of the housing.

I preferably provide a removable form block 38 which is mounted on the table between the presser blocks in any approved manner, such, for instance, as by screws 10 threaded into sockets provided in the table, or by mounting studs on the table, fitting into sockets in the block. I also provide ejecting means for removing a pressed box body from the block. This means may include a plunger rod 39, passing through a longitudinal guide passage in shaft 33 and through a registering bore in block 38, the outer end of plunger 39 carrying an ejecting plate 40, normally resting in a countersunk 15 recess in the face of block 38, the ejector plate being, if desired, threaded on or otherwise removably attached to, plunger 39 to facilitate detachment of the plate and removal of the block when a new block is to be substituted. 20 The ejector is reciprocated to remove pressed box bodies by means of an ejector lever 41 connected by link 42 to a collar 43 threaded on plunger 39 and held in adjusted position by nut 44. The plunger can be adjusted to 25 various heights of block 38 by varying the location of collar 43 on the plunger and, if desired, the plunger 39 may be entirely removed to change block 38 by unscrewing it from collar 43 and nut 44. The ejector 30 lever 41 is pivotally mounted on a bracket 46 mounted on casing 37, the pivot 45 carrying for convenience the end of the ejector lever 41 of the adjoining press. Lever 41 may be operated by various means. I prefer 35 to form gear teeth 47 on the periphery of cam 32, meshing with a pinion 48 mounted on stub shaft 49, which is shouldered and mounted in the same manner as shaft 33 in sockets in the table 13 and casing 37. 40 Mounted on, and preferably integral with, pinion 48 is a cam disk 50 having a peripherally upstanding cam ridge 51 which is of the same height throughout except for a short depression therein at 52. A rod 53 45 slidable in a bore in the casing 37 rests on the face of the cam ridge and has at its upper end fork 54 carrying a pin passing through a short slot in the ejecting lever 41. The lever is normally pulled toward table 50 55 by spring 55 attached at one end to said lever and at the other end to the casing, preferably being attached for convenience to a projection on the end of stub shaft 49. Both presses are driven by a single drive 60 shaft 56 mounted in the rear of table 13 in bearings in frame members 10 and 11. Worms 57 are mounted on drive shaft 56 adjacent worm gears 35 and mesh therewith through apertures in casing 37. If desired, 65 however, casing 37 may be formed to act as

a housing for worms 57. Shaft 56 may be driven in any approved way. I have shown one form of drive, including a drive pulley 58 mounted loosely on the shaft, having the usual spring-pressed conical clutch 59 normally in engagement therewith. As shown in Fig. 1, a fork 60 engages collar 61, the clutch member being controlled through link 62 connected to the fork and pivoted on starting lever 63, the rear end of which is provided with a bearing on frame member 10, the handle end of the starting lever extending through a slotted holder 64 at the front of the frame, a shoulder 65 in said holder serving to retain the starting lever in position when the clutch is thrown out against the action of spring 66. Pulley 58 may be driven from any suitable source of power. I have shown a motor 67 mounted on the frame of the machine and connected by a belt to the pulley.

I also provide a conveyer for removing the pressed boxes. This conveyer may be in the form of an endless belt 68, located in front of and adjacent the lower edge of table 13, the belt running at its left hand end over roller 69, preferably mounted on an adjustable bracket 70, carried by the frame member 10. The other end of the belt conveyer runs over roller 71 mounted on shaft 72, carried by brackets 73 on end frame 11, shaft 72 being driven from drive shaft 56 in any desired manner. I have disclosed a gear train for this purpose, comprising a pinion 74 mounted on the end of shaft 56 90 and meshing with pinion 75, carried by a stud on frame member 11, which in turn meshes with a pinion 76, also mounted on a stud on said frame member. A bevel gear 77 is fixed on the outer side of said pinion 75 and meshes with bevel gear 78 mounted on shaft 72. Housing 79 attached to frame member 11 is provided to protect the gear train. A neck gluer 80 may be mounted in any desired manner at the rear of the frame 95 and adjacent table 81, which is mounted on brackets along the right hand end of the machine, and extends to the front thereof, so that the gluer operator may slide the loosely necked boxes along the table to the neck presser operator.

I also provide means for guiding the falling boxes ejected from the press to conveyer belt 58. In the form shown, said means consists of a board or plate 82 located 100 adjacent the outer edge of the belt and facing table 13, the board being preferably supported by brackets 83 attached to the table 13. This board 82 not only guides falling boxes to the conveyer, but prevents their 105 being knocked off the conveyer during the travel thereon.

While I have shown the conveyer as extending only to the left end of the machine, obviously it might be extended as far as de- 110

sirable therebeyond to convey the pressed boxes to the next operator.

In the operation of the machine, a suitable form block 38 is first fixed in place in each press and ejector plate 40 fastened in position. Bolts 25 are loosened, and the carrier heads are slid inwardly until presser blocks 14 are in proper relation to block 38. In 10 pressing narrow or small boxes, a convenient method of arranging presser blocks 14 is to have the left hand end of each block located against the face of the adjacent presser block, the right hand end of each block when the press is in closed position 15 projecting beyond the end of the presser block to its right. In this manner, boxes having dimensions smaller than the length of the presser block may be properly pressed. Clamp screws 17 facilitate ready adjustment 20 of the blocks. This method of arrangement is, of course, applicable only to straight-sided boxes. The carrier heads 21 are then clamped in position by tightening bolts 25 and the presser is started by manipulating 25 the starting handle 65 to throw in the clutch so that drive shaft 56 rotates cams 32 through worm gears 57. Presser carrier heads 24 are reciprocated through cam rollers 30, the cam slot 31 being so shaped that 30 the slides of each press are simultaneously moved outwardly and inwardly, producing opening and closing motions of blocks 14. Ejector plate 40 is normally held in the recess in block 38, but when the press starts 35 to open, rod 53 drops into recess 52 in cam flange 51, depressing the ejector lever 41, which pushes plunger 39 outwardly. The continued rotation of cam 50 pushes rod 53 up out of recess 52, retracting the plunger 40 and preparing the block for the reception of a box. The operation of adjacent presses is so timed that the ejectors work alternately. The operator, when the press is in motion, takes a box body, with the neck loosely inserted therein, from table 81 where it has 45 been placed by the gluer operator, and positions it on a block 38 as soon as the ejector plate 40 has returned to position in the block. The press then closes on the box, the adjacent press simultaneously opening to eject its 50 box and receive another. When the press closes, blocks 14 are resiliently pressed against the sides of the box by springs 22, and by regulating the pressure of the springs 55 by means of screw plugs 23, the amount of pressure on the box sides may be regulated, and uneven pressure at opposite ends may be avoided, thus compensating for variations in the springs.

60 It will also be noted that the connection between blocks 14 and carrier heads 21 is entirely flexible, allowing the blocks to move vertically as well as horizontally, permitting the block faces to accommodate themselves to the irregularities in the box. This

is of particular value when the box is not rectangular in form, and the block is shaped to conform thereto.

When the box has been pressed and the press opens, ejector plate 40 rises, pushing 70 the box off the block 38. When free of the block, the box falls to conveyer bolt 68, being guided thereto by board 82, and is then carried to the left hand end of the machine, where it may be disposed of in any desired 75 way, such as by falling into a receptacle, by being carried on by another conveyer or being received by the succeeding operator. As soon as the box is ejected, the operator immediately replaces it with another box. 80 This operation can be performed at a relatively rapid rate of speed, as it consists simply of picking up the light box body and positioning it on block 38, the removal of the box from the press and from the machine 85 being automatic. The machine is also arranged so that the box can be placed on the form block by a relatively short motion of the operator and without leaning over the table, as was necessary with the former type 90 of press.

It will be apparent that the parts are so arranged that they can be readily removed and replaced. As above pointed out, each presser block unit may be removed by itself 95 without disturbing the rest of the machine, and the ways which are subject to considerable wear, may be very readily replaced. The entire drive mechanism may be exposed by detaching the plungers 39 and the rear 100 casing 37 and removing table 13. Casing 37 may also be divided in sections, so that parts thereof may be removed and the operative portion of the mechanism readily taken out and repaired or replaced. Each press is a 105 complete unit, and any derangement thereof may be repaired, without stopping the other press, by disconnecting the deranged press from the drive through the removal of worm gear 35. 110

While I have described a specific embodiment of my invention, it will be apparent that many modifications may be made therein without departing from the spirit of my invention or the scope of the claims. 115

What I claim is:

1. In a machine for pressing necks in boxes, a stationary support, two forms secured to the support, each adapted to receive an externally located assembled box and neck for pressing, pressing means co-operating with each form to press the sides of the box assembly located thereon, and means for operating the two pressing means alternately. 120

2. In a machine for pressing necks in boxes, a support, two forms mounted on the support, each adapted to receive an assembled box and neck for pressing, pressing means co-operating with each form to press 130

- the sides of the box assembly located thereon, an ejector for the box assembly located on each form, means for operating the two pressing means alternately, and means for 5 operating the two ejectors alternately so that each ejector acts when the corresponding pressing means is in inoperative position.
3. In a machine for pressing necks in boxes, an approximately vertical table, two forms mounted on one side of the table and each adapted to receive an assembled box and neck for pressing, a plurality of pressing elements coöperating with each form to 10 press the sides of the box assembly located thereon, operating means for each plurality of pressing elements, and means for actuating the two operating means alternately.
4. In a machine for pressing necks in boxes, an approximately vertical table, two forms mounted on one side of the table and each adapted to receive an assembled box and neck for pressing, a plurality of pressing elements coöperating with each form to 15 press the sides of a box assembly located thereon, an ejector for each form, operating means for each set of pressing elements arranged to act alternately, and means for operating the ejectors alternately so that each 20 ejector acts when the corresponding pressing elements are retracted.
5. In a machine of the class described, an internal form adapted to receive a glued box body and neck, a stationary support upon 25 which the form is mounted, means carried by said support for pressing said box body and neck against the form and means for removing the box body and neck from the 30 form.
6. In a machine of the class described, a support, a table mounted in an approximately vertical position on said support, a form adapted to receive a box body and neck located on one side of the table, and pressing 35 means mounted on said table and arranged to coöperate with the form.
7. In a machine of the class described, an approximately vertical table, a form adapted to receive an assembled box body and neck and a coöperating pressing means 40 mounted on one side of the table, and a conveyer located below and in front of said pressing means to receive and remove articles which have been pressed therein.
8. In a machine of the class described, an approximately vertical table, pressing means 45 mounted thereon, a conveyer in front of and below said pressing means and means for removing a pressed article from said pressing means to be received and carried off by the conveyer.
9. In a machine for pressing glued and assembled box bodies and necks, a stationary support, an internal assembly receiving 50 form located on the support, pressing means coöperating with the form and carried by the support, an ejector for removing the pressed assembly from the form, and conveying means located adjacent the pressing means in such a manner that pressed articles, when removed, will fall upon the conveyer by gravity.
10. In a machine for pressing glued and assembled box bodies and necks, a stationary support, an internal assembly receiving 55 form located on the support, pressing means coöperating with the form and carried by the support, an ejector for removing the pressed assembly from the form, a conveyer located adjacent thereto in position to receive an article ejected from said pressing means, and means for guiding the article from the press to the conveyer.
11. In a machine of the class described, an approximately vertical table pressing means, 60 means for ejecting a pressed article therefrom in an approximately horizontal direction, a conveyer located to receive a pressed article falling from the press, and a plate located in the path of the ejected article to 65 direct it to the conveyer.
12. In a machine for pressing assembled box bodies and necks, a plurality of adjacent stationary presses each comprising an internal form to receive an assembled and 70 glued box part and neck and a plurality of pressing elements coöperating with the form, a support for the presses, and a conveyer passing close to the presses to receive articles discharged therefrom.
13. In a machine of the class described, an approximately vertical table, pressing means mounted on the front thereof, a presser-drive shaft in the rear of the table, a carry-off conveyer in front of the pressing means and 75 means for driving the conveyer from said drive shaft.
14. In a machine for pressing assembled box bodies and necks, a stationary support, an internal form fixed thereon for receiving 80 the assembly, a plurality of reciprocating pressing elements adapted to simultaneously press the sides of the assembly against the form, and a unitary actuating element for simultaneously reciprocating all of said 85 pressing elements.
15. In a machine for pressing assembled box bodies and necks, a stationary support, an internal form fixed thereon for receiving 90 the assembly, a plurality of reciprocating pressing elements adapted to simultaneously press the sides of the assembly against the form, and a single cam for simultaneously reciprocating all of said pressing elements.
16. In a machine of the class described, a 95 form for holding box parts to be pressed, a plurality of presser elements coöperating with the form, a slide for each element, cam engaging means mounted on each slide, and a cam having a single track receiving all of 100

said cam-engaging means for simultaneously reciprocating said presser elements.

17. In a machine for pressing assembled box bodies and necks, a stationary support, 5 a press thereon including an internal form for holding an assembled box body and neck and a plurality of reciprocating pressing elements adapted to coöperate with the form simultaneously to press the sides of the box 10 assembly, means for reciprocating said pressing elements, and means for ejecting the assembly from the press.

18. In a machine for pressing assembled box bodies and necks, a stationary support, 15 a press thereon including an internal form for holding box parts or the like and a plurality of reciprocating pressing elements co-operating with the form to simultaneously press the sides of the box, driving means for 20 reciprocating said elements, means for ejecting an article from the press, and means for operating said ejector from said driving means.

19. In a machine of the class described, a 25 press including a form and a plurality of reciprocating presser members adapted to press the sides of an article against the form and an ejector within and located beneath said article and adapted to be extended to 30 push the article out of the press.

20. In a machine of the class described, a form and a plurality of presser members adapted to press the sides of an article against the form and a reciprocating plunger 35 located between said presser elements and beneath and within the pressed article, adapted to be projected to remove the article from the press.

21. In a machine of the class described, a 40 form block, presser elements adapted to press an article against the form block, a plunger mounted in said form block, and means for projecting said plunger to remove the pressed article from the block.

45 22. In a machine of the class described, a support, presser elements on the face of said support, driving means on the rear of said support for reciprocating the presser elements, a plunger extending through said 50 support, a cam for operating said plunger to eject a pressed article, and a driving connection between said driving means and said cam for synchronizing the action of the presser elements and the plunger.

55 23. In a machine of the class described, a plurality of presser elements, a plurality of

slides carrying said elements, a cam for simultaneously reciprocating said slides, a plunger extending into the space between said presser elements, a cam for reciprocating said plunger to eject pressed articles and driving connections between said cams. 60

24. In a machine for pressing assembled and glued boxes and necks, a support, an internally assembled receiving form mounted 65 on the face of said support, coöperating pressing elements mounted on said support, a cam for driving said elements removably mounted on the rear of said support, and means for rotating said cam. 70

25. In a machine of the class described, a support, presser elements mounted on the face of said support, a cam for reciprocating said presser elements removably mounted on the rear of said support, a gear removably 75 mounted on the cam and a drive shaft connected to said gear for rotating the cam.

26. In a machine of the class described, a slide, means for reciprocating said slide, a carrier head adjustably mounted on the slide, 80 a clamp resiliently mounted on the carrier head, a presser element carried by the clamp, and a relatively fixed coöperating presser element.

27. In a machine of the class described, a reciprocating carrier head, a clamp mounted 85 on the carrier head, a presser block carried by the clamp, resilient means for holding the clamp in position in the carrier head, and means for adjusting said resilient means, 90 and a relatively fixed, coöperating presser element.

28. In a machine of the class described, a reciprocating carrier head, sockets located in the head, a clamp, studs mounted on the 95 clamp and slidable in said sockets, a presser member carried by the clamp, resilient means bearing on the studs, and means for adjusting the resilient means.

29. In a machine of the class described, a 100 substantially vertical table, pressing means mounted thereon, said means comprising a form arranged at one side of the table and a plurality of laterally moving presser elements coöperating with the form, a feed 105 table adjacent one end of the press, and a conveyer running from the feed table and adjacent to the press.

In testimony whereof I have hereunto set my hand.

CHARLES H. NITSCH.
